(57) **CLAIM**

The ornamental design for a vertical fall arrest safety device, as shown and described.

DESCRIPTION

FIG. 1 is a top plan view of a vertical fall arrest safety device, showing our new design;

FIG. 2 is a bottom plan view thereof;

FIG. 3 is a left elevation view thereof;

FIG. 4 is a front elevation view thereof;

FIG. 5 is a right elevation view thereof;

FIG. 6 is a left top perspective view thereof;

FIG. 7 is a left bottom perspective view thereof;

FIG. 8 is a right top perspective view thereof;

FIG. 9 is a right bottom perspective view thereof;

FIG. 10 is right rear perspective view thereof;

FIG. 11 is a left rear perspective view thereof;

FIG. 12 is a left rear perspective disengaged view thereof;

FIG. 13 is a right rear perspective exploded view thereof;

and,

FIG. 14 is a right front perspective exploded view thereof.

The broken lines shown in the figures are for the purpose of illustrating environment and form no part of the claimed design.

1 Claim, 14 Drawing Sheets
